UNITED STATES PATENT OFFICE.

GEORG FRIEDRICH LEBIODA, OF PARIS, FRANCE.

APPARATUS FOR DYEING AND IMPREGNATING WOOD.

SPECIFICATION forming part of Letters Patent No. 609,442, dated August 23, 1898.

Application filed December 29, 1897. Serial No. 664,337. (No model.) Patented in Belgium July 8, 1897, No. 127,364.

To all whom it may concern:

Be it known that I, GEORG FRIEDRICH LEBIODA, a subject of the King of Prussia, Emperor of Germany, residing at the city of Paris, in the Republic of France, have made a new and useful Invention in Improvements in Apparatus for Impregnating and Dyeing Wood, (for which I have obtained Belgian Patent No. 127,364, dated July 8, 1897,) of which the following is a specification.

This invention relates to an apparatus for impregnating and dyeing or coloring wood, a suitable fluid being passed, under a high pressure, longitudinally through the fibers of the wood in the manner of filtration and in a constant stream. The said liquid may be a dye-stuff or may contain adhesive substances, such as albumen, gum, and resin. Certain oils, metallic salts, or antiseptic or decomposition-preventing liquids may also be employed.

The improved apparatus consists of a cylinder, open below and closed above, and a cylinder closed below by a sieve or straining-plate, which latter cylinder is directly attached to the upper one by means of flange-rings or the like. In this cylinder or receptacle the wood to be treated is placed, after having been first cut with a smooth surface, so as to stand level on the sieve-plate. The holes left free by the wood in the sieve-plate are stopped with plugs, and a thin layer of some suitable substance which hardens when cold is poured over it. The liquid is finally conveyed, under high pressure, into the receptacle and forced through the wood to be treated, after which the liquid, after depositing the dye or impregnating substances in the fibers of the wood, is discharged through the sieve-holes under the lower part of the wood.

The improved apparatus is so arranged that the vessel receiving the wood may be closed below by an under piece and be open above in order to force the liquid upward through the wood from below, if desired. The under part is adjustable in height by means of a screw-spindle, and during the impregnation from above is so far lowered that the workman can see the discharge of the liquid through the sieve-plate. The underneath vessel also serves as a receiver for the liquid, which may then be carried off by means of a discharge or catch pipe. In proximity to the

sieve-plate the wall of the lower cylinder is further provided with a hollow space, in which after the completion of treatment of the wood 55 steam may be admitted in order to soften the substance employed for closing the holes in the sieve which are not covered by the wood and for fixing the wood.

This improved apparatus is shown in the 60 accompanying drawings, in which—

Figure 1 is a vertical section; Fig. 2, a horizontal section on the line xx of Fig. 1; Fig. 3, a section on the line yy of Fig. 2; Fig. 4, a section on the line zz of Fig. 2. 65

The vessel intended to receive the wood to be treated consists of an upper cylinder a and an under cylinder b , in which a bottom plate d , provided with a flanged ring c and having numerous holes, is inserted from below. The two cylinders a and b are connected by flange-rings e and e' and bolts f . The lower cylinder b has an internal iron casing b' and is carried by three supports or standards g . The bottom plate d is secured to the lower ring-flange 70 of the cylinder b by means of screw-bolts h . Washer-rings i are provided between the cylinders b and a and between the cylinder b and the sieve-plate d , which produces a tight joint even under high pressure. The cylinder a is closed above by means of a collar a' , in which a manhole closed by a cover m and carrying rings o are provided. The cylinder a has also a safety-valve k and a manometer l . An additional part p is arranged under the 75 perforated bottom plate d , which part p may be suitably adjusted vertically by means of a screw-spindle p' and is revolute in a support p^3 by means of a revolute hand-wheel p^2 . The flat edge of the part p engages with an 80 annular groove over an annular projection of the bottom plate d' . Between both plates a washer-ring i' is arranged and compressed when the lower nuts h' of the bolt h are tightened. A discharge-opening q , provided with 85 a discharge-pipe q' , which is capable of being closed, is arranged in the under part p . A funnel q^2 , attached to a discharge-pipe q^3 , is arranged beneath the opening q , through which pipe the liquid can be discharged when 90 the pipe q' is opened. A tap or cock r , Fig. 3, is inserted in the cylinder b , through which liquid under pressure can be pumped or forced into the interior of the cylinders a and b . A

tap s on the bottom plate d is also provided, through which liquid under pressure can be pumped under the bottom plate.

In order to be able to discharge, if desired, 5 the liquid contained in the receptacles, the cylinder b is also provided with a discharge-tap u . The flange-ring c of the bottom plate d is also provided with a broad annular groove or channel, in which steam may be admitted 10 through a tap t , Fig. 4, as will be hereinafter described. Another tap t' serves for letting off the steam and the liquid condensed therefrom, and a further tap t'' is inserted in the bottom plate d itself, Fig. 4, in order to allow 15 steam to be conveyed under the sieve-plate even when the under part p is pushed up in its highest position.

The mode of working of the apparatus hereinbefore described is as follows: The 20 screws or bolts f are slackened, and the upper cylinder a is raised, by means of the lifting-rings o , from off the lower cylinder b . The under part p is then brought into its lower position by means of the hand-wheel p^2 . The 25 wood A to be treated, which is cut smooth on its faces, is placed on the sieve-plate d , and the holes in the bottom plate which remain uncovered by the wood are closed by means of wooden plugs. A cement or substance, such 30 as resin or tar, capable of being melted is then poured between the pieces of wood and the inner wall of the cylinder. On this substance setting a cement-like layer a few centimeters in height forms a tight joint or closing to the 35 lower part of the cylinder, and the said layer also serves to keep the wood in position. The cylinder a is then again brought into its position and screwed tight by means of the bolts f , a good joint being obtained by reason 40 of the washer-rings employed. The liquid under pressure is then allowed to enter the receptacle through the tap r , which liquid only finds an exit through the wood and the holes beneath the same. The sap is thus expelled 45 from the wood, and the liquid under pressure takes its place. As the under part p is lower than the cylinders, the discharge of the sap and the liquid under pressure through the holes in the bottom plate may be readily 50 observed. After the liquid has penetrated every fiber of the wood along its entire length a first time it may be caught on its discharge from the openings of the plate d in the lower part p and, by opening the pipe q' , carried 55 off through the pipe q^3 , in order to be forced through the wood for a suitable second treatment.

In case the liquid under pressure has to be discharged from the wood-receptacle without 60 passing through the sieve-plate and part p the tap u is opened.

After the liquid under pressure has acted sufficiently from above it is allowed to pass from below under the bottom plate d . To 65 enable this to be done, the under part p is raised by means of the hand-wheel p^2 and fastened by means of the nuts h' of the bolts

h while the washer-ring i' is compressed. The tube or nozzle q' is then tightly closed and the manhole-cover removed. The tap is 70 now opened, and the liquid under pressure passes under the bottom plate and penetrates from below upward through the wood. When the impregnation is completed, the liquid is allowed to run off, and steam is conveyed 75 through the taps t and t' into the annular channel around the flanged ring c , as well as under the bottom plate d , whereby the layer of cement, resin, or the like employed for closing the holes not covered or closed by the 80 wood and for holding the wood in position is softened. The upper cylinder is then lifted and the finished wood removed in order to be replaced by a fresh supply, after which the process hereinbefore described is repeated. 85

This invention is of great advantage in that the impregnation takes place in the direction of the fibers and the pressure may be allowed to rise up to a certain degree, which can be easily and exactly ascertained by 90 means of the manometer. A further advantage is that no special form need be given to the wood, and the coloring of the wood by impregnation by a cold process may take place, so that the fibers of the wood are not 95 in any way affected. Finally, by the present invention timber—such, for instance, as railway-sleepers—may be so thoroughly impregnated with a decay-resisting substance that it cannot decay, and thereby very great durability is imparted to it. 100

Having now particularly described and ascertained the nature of my said invention and in what manner the same is to be performed, I declare that what I claim is— 105

1. In combination, the vessel adapted to receive the wood to be treated and having a perforated bottom to support the wood, the removable under part p adapted to form a chamber beneath the perforated bottom, the threaded standard and hand-wheel for raising and lowering said part p , and the admission and exit valves to said vessel and chamber for the treating fluid, substantially as described. 115

2. In combination, the vessel for the wood composed of two parts a b detachably connected together, the perforated bottom plate abutting against the lower edge of said vessel and having an annular flange extending up within the vessel and abutting against an annular shoulder within the vessel, said flange forming with the wall of the vessel an annular steam-channel, steam inlet and exhaust ports to said chamber, a removable under part p 120 forming a chamber beneath the perforated plate, and admission and exit valves for the treating liquid, substantially as described. 125

In witness whereof I have hereunto set my hand in presence of two witnesses.

GEORG FRIEDRICH LEBIODA.
